(57) **CLAIM**

The ornamental design for a winch line adjustment device, as shown and described.

DESCRIPTION

FIG. 1 shows a perspective view of a winch line adjustment device;

FIG. 2 shows a front elevation view of the winch line adjustment device;

FIG. 3 shows a rear elevation of the winch line adjustment device;

FIG. 4 shows a right side elevation view of the winch line adjustment device;

FIG. 5 shows a left side elevation view of the winch line adjustment device;

FIG. 6 shows a top plan view of the winch line adjustment device; and,

FIG. 7 shows a bottom plan view of the winch line adjustment device.

The shade lines in the Figures show contour and not surface ornamentation.
